UNITED STATES PATENT OFFICE.

FREDERICK J. KLINGLER, OF SAGINAW, MICHIGAN.

ROTARY INTERNAL-COMBUSTION ENGINE.

1,324,506.

Specification of Letters Patent.

Patented Dec. 9, 1919.

Application filed June 14, 1919. Serial No. 304,098.

To all whom it may concern:

Be it known that I, FREDERICK J. KLINGLER, a citizen of the United States, and a resident of Saginaw, Saginaw county, and

- 5 State of Michigan, have invented certain new and useful Improvements in Rotary Internal-Combustion Engines, of which the following is declared to be a full, clear, and exact description.
10 This invention relates to rotary internal combustion engines, and its primary object is to dispense with the usual valves and operating mechanism therefor. Another object is to provide a rotary internal combustion engine in which the pistons are carried by a rotating member which is mounted upon the drive shaft, the cylinder or explosion chamber in which the explosions occur being stationary. Another object is to provide
15 20 a rotary combustion engine with a rotating member, having a plurality of pistons therein, whereby several impulses may be had during each rotation of the drive shaft. With these and other objects and advantages
25 in view this invention consists in the several novel features of construction and arrangement fully set forth in the following specification, and particularly defined in the claims.

30 The invention is clearly illustrated in the accompanying drawings, in which:

Figure 1 is a front elevation, partly broken away, of a rotary internal combustion engine, containing a simple embodiment
35 of the present invention;

Fig. 2 is a detail, enlarged section of fragments of the casing, piston carrier and two pistons, taken on the line 2—2 of Fig. 1;

Fig. 3 is a vertical cross section taken
40 on the line 3—3 of Fig. 1;

Fig. 4 is a plan of a pair of pistons;

Fig. 5 is a section taken on the line 5—5 of Figs. 1 and 3, and showing the parts laid out flat;

45 Fig. 6 is a view similar to Fig. 5, but showing the parts in a different position;

Fig. 7 is an end view of the heads or cam shoes seen in Fig. 4, and

Fig. 8 is a detail side elevation of one of
50 said heads or cam shoes, and a certain abutment member.

Referring to said drawings, the reference character 10 designates a cylindrical casing, comprising a cylindrical wall 11, and heads
55 12, 13, bolted or otherwise secured thereto. On the head 12 is the explosion chamber 42.

Lugs or brackets 14 may be provided on the casing for securing the motor to any suitable frame work or other support.

Journaled in bearings on said casing is a 60 main drive shaft 15, which has rigidly secured thereon a rotary piston carrier 16, or wheel for carrying the pistons 20, 21, said carrier 16, comprising an annular rim portion 17 connected to a hub 18 by spokes 19. 65 The contiguous faces of the rim portion 17 and head 12 are machined to fit perfectly, and if desired, packing rings 17^a may be interposed between said faces to prevent leakage of the explosive fluid at this place. 70

The rim portion 17 of the piston carrier 16 is bored transversely at a plurality of places to provide cylinders 20^a, 21^a, for the reception of the pistons 20, 21. Keys 21^x secured to the pistons and running in key- 75 ways formed in the walls of the cylinders, prevent relative rotation between the pistons and carrier. The pistons 20 act to compress air in the cylinders 20^a, for the charges, and the pistons 21 receive the impulses 80 from the exploded charges in the explosion chamber. The compression pistons 20 and explosion pistons 21 are arranged in pairs (see Fig. 4), and in the operation of the engine are reciprocated trans- 85

versely of the piston carrier. In the form of the invention illustrated, the pistons have piston rods 22, 23, secured to them, which are provided upon their ends with heads or cam shoes 25, 26. Two rotating cams, 27, 28, are employed for moving the pistons during the compression strokes, said cams acting against the outer faces of the heads or cam shoes, 25, 26, during the intervals that said heads or cam shoes pass the cams. 95 The cams 27, 28, are rigidly secured upon a cam shaft 29 which is mounted in bearings 30, and has a beveled pinion 31 upon its end, which meshes with a beveled gear wheel 32 fast upon the main drive shaft 15. The ratio of the gearing is such that the cams 27, 28, engage with the heads, or cam shoes of the piston rods as they pass the cams and move the pistons to the outer limits of their strokes. 100

The cam 28 is set slightly in advance of the cam 27, and operates to project the explosion piston 21 to the limit of its outer stroke in contact with the wall 38 of the explosion chamber 42, before the cam 27 moves 110 the associated compression piston 20 to the extreme end of its compression stroke. The

purpose of this construction and arrangement is to prevent the compressed air from being forced past the explosion piston when being discharged from the compression cylinder into the explosion chamber. The 5 ends of the cylinders 20^a adjacent the explosion chamber are provided with heads 17^c (see Fig. 2), in which are formed ports 17^b that establish communication between 10 the compression cylinders 20^a and explosion chamber 42 when the ports 17^b reach the open side of the explosion chamber, that is, the side adjacent the piston carrier. The arrangement of the compression piston 20 15 and its cam 27 is such that at the extreme end of its compression stroke, the head of the piston is brought practically into contact with the face of the head 17^c of the compression cylinder 20^a—thereby expelling all 20 the air from the compression cylinder.

To hold the pistons at the outer limits of their strokes, and to retract them, I provide circular cam tracks 33, 33^a, supported from the casing by brackets 34, which cam 25 tracks coöperate with rollers 35, 35^a, mounted on the piston rods, 22, 23. The cam tracks have abrupt angularly disposed cam portions 36 which coöperate with the cams 27, 28, in moving the pistons to the outer 30 limits of their strokes; portions 37, parallel with the wall 38 of the explosion chamber, 42, inclined cam portions 39, parallel with the oblique wall 40, and portions 41, parallel with the wall 12 of the casing. The parts 37 of 35 the cam tracks act to hold the pistons at the outer limits of their strokes; the cam portions 39 act to retract the pistons, and the parts 41 of the cam tracks act to hold the pistons in retracted position until they reach 40 the cam portions 36 and cams 27, 28.

The cylinder or explosion chamber 42 is in the form of an arc of a circle concentric with the main drive shaft 15, and it has an abrupt oblique end wall 43 and a gradually 45 inclined oblique end wall 40. In the end wall 43 is formed an opening 44 into which is screwed the fluid feed pipe (not shown) and adjacent thereto is a spark plug 45 which is connected to the ignition system in 50 the usual manner by mechanism (not shown), and said mechanism may be operated from the main drive shaft for closing the circuit through the spark plug at the proper intervals to ignite the compressed 55 charge in the explosion chamber. Air intake ports 46, 46^a, are formed in the head 12 of the casing and may be connected by an arcuate air passage 46^a which may be in the nature of a groove formed on the inner face 60 of the head 12, and said inner ports and arcuate air passage open to the compression cylinders through the ports 17^b when they pass along the arcuate groove. The exhaust port 47 is provided at the small end

of the explosion chamber, as is clearly 65 illustrated in Fig. 5.

The explosion chamber may be substantially semi-circular in cross section and the end 49 of the explosion piston is rounded off to fit the internal wall of said chamber 70 42. The working face 50 of the explosion piston is beveled off at the same angle as the end wall 43 of the explosion chamber. The pistons have piston rings 51 to make tight joints with the walls of the cylinders and explosion chamber. The explosion chamber 75 may be formed of a separate part bolted or otherwise fastened to the casing.

While the charges are being exploded, there is considerable end thrust imparted 80 to the explosion pistons, and to resist such end thrust, I have provided an abutment member 52 secured to the casing, along which the heads or cam shoes 26, run during the intervals that the explosion pistons 85 travel in the explosion chamber. Said abutment member is solidly constructed and takes up the end thrusts of the explosion pistons. Preferably anti-friction rollers 53, are mounted in the heads or cam shoes 26, 90 and roll along the abutment member.

The operation of the engine is as follows:

The piston carrier rotates in the direction of the arrow α , in Figs. 1, 5 and 6, and carries the pistons past the air inlet ports 95 and air passage, and through the arcuate explosion chamber. Except when passing through the explosion chamber, the pistons are held in retracted positions by the cam tracks, 33, 33^a, and such position is illustrated in Fig. 5. As each piston 20 passes the air inlet port 46, and the air passage 46^a, air enters the compression cylinder through the port 17^b, and after the port 17^b of the cylinder 20^a has passed the inlet 105 port 46^b, the air is trapped in said cylinder, 20^a, between the head of the piston 20, and head 17^c of the cylinder, and face of head 12 of the casing, covering the port 17^b. When the explosion piston 21 reaches the 110 position seen in Fig. 5, the cam 28 is in position to engage the head or cam shoe 26 of the piston rod 23 and commences to move said head, and therewith the explosion piston 21, toward the wall 38 of the explosion 115 chamber, and as the piston carrier continues to revolve, the cam 27 comes into contact with the head of the piston rod 22 and moves the compression piston toward the head 17^c of the cylinder 20^a, thereby compressing the air confined in said cylinder. The throw of the cam 28 is sufficient to bring the explosion piston into contact with the internal face of the wall 38 of the explosion chamber 42. Said explosion piston 120 reaches the limit of its outer stroke, in position immediately behind the oblique wall 43 of the explosion chamber (see Fig. 6),

and the compression piston reaches the limit of its compression stroke just as the port 17^b passes the adjacent edge of the oblique wall 43, thereby discharging the compressed air from the cylinder 20^a into the explosion chamber behind the explosion piston. It is to be understood that the compressed air is confined in the end of the compression cylinder 20^a until the port 17^b reaches and passes the adjacent edge of the oblique end wall 43, thereby establishing communication between the compression cylinder 20^a and the explosion chamber 42, at which time the charge of explosive fluid is injected under pressure through the port 44, and the circuit through the spark plug 45 is closed, whereby the charge is ignited between the oblique faces of the explosion piston and explosion chamber, and the explosion piston 21 is forced along the arcuate explosion chamber. As soon as the rollers 35 reach the oblique portions 39 of the cam track the pistons are retracted and the explosion chamber is opened, behind the explosion piston, to the outer atmosphere, through the discharge port 47. The succeeding explosion piston, in traveling through the explosion chamber, forces out any burnt charge that may remain in said explosion chamber.

Obviously, the number of pairs of pistons may be increased or diminished, as desired, and the number of explosion chambers and piston actuating means may be increased and disposed equidistant around the casing, and in this manner each explosion piston may be given several impulses during each cycle of rotation of the carrier.

No attempt has been made to illustrate cooling and oiling means, but the engine may be air cooled or water cooled, and oiled by any familiar means, as is found most satisfactory.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. In a rotary internal combustion engine, the combination with a cylindrical casing having an arcuate explosion chamber thereon concentric with the axis of the casing, of a rotary piston carrier mounted in said casing, a compression piston and an explosion piston slidably mounted in said carrier to reciprocate in lines parallel with the axis of the casing, and means for reciprocating said pistons to compress charges and to project the explosion piston into the explosion chamber, and to retract it therefrom.

2. In a rotary internal combustion engine, the combination with a cylindrical casing having an arcuate explosion chamber thereon concentric with the axis of the casing, of a rotary piston carrier journaled in said casing and being bored transversely for the reception of pistons, compression pistons and explosion pistons arranged in pairs slidably mounted in said bores, and means for reciprocating said pistons in said bores, to compress the air and to project the explosion pistons into the explosion chamber. 65

3. In a rotary internal combustion engine, the combination with a cylindrical casing having an arcuate explosion chamber concentric with the axis of the casing, said explosion chamber having an oblique end wall, of a rotary piston carrier journaled in said casing, compression pistons and explosion pistons arranged in pairs and mounted to slide in said carrier, the explosion pistons having oblique working faces, and means for reciprocating said pistons in the carrier to compress the charges and to project the explosion pistons into the explosion chamber. 80

4. In a rotary internal combustion engine, the combination with a cylindrical casing having an arcuate explosion chamber thereon, provided with an oblique end wall, of a rotary piston carrier journaled in said casing and bored transversely for the reception of pistons, compression pistons and explosion pistons arranged in pairs and slidably mounted in said bores, said explosion pistons having oblique working faces, 100 and means for reciprocating said pistons in the carrier to compress the charges and to project the explosion pistons into the explosion chamber. 90

5. In a rotary internal combustion engine, the combination with a cylindrical casing having an arcuate explosion chamber thereon formed with an oblique end wall, of a rotary piston carrier journaled in said casing, compression pistons and explosion pistons mounted to reciprocate in said carrier, said explosion pistons having oblique working faces and means for reciprocating said pistons, including timing mechanism constructed and arranged to compress 115 the charges and project the explosion pistons into the explosion chamber. 105

6. In a rotary internal combustion engine, the combination with a cylindrical casing having an arcuate explosion chamber formed with an oblique end wall, of a drive shaft journaled in said casing, a rotary piston mounted on said drive shaft and bored transversely for the reception of pistons, compression pistons and explosion pistons slidably mounted in said bores, said explosion pistons having oblique working faces, 120 said compression and explosion pistons being 125

4
arranged in pairs and those of each pair moving in unison, and means for reciprocating said pistons to compress the charges and to project the explosion pistons into the explosion chamber.

5 7. In a rotary internal combustion engine, the combination with a cylindrical casing having an arcuate explosion chamber formed with an oblique end wall, of a main drive shaft journaled in said casing, a rotary piston carrier mounted on said drive shaft, compression pistons and explosion pistons arranged in pairs and slidably mounted in said carrier, the explosion pistons having oblique working faces, piston rods, one connected to the pistons of each pair, a cam shaft, cams thereon adapted to engage said piston rods to project said pistons and gearing between said drive shaft and cam shaft.

10 8. In a rotary internal combustion engine, the combination with a cylindrical casing having an arcuate explosion chamber formed with an oblique end wall, of a main drive shaft journaled in said casing, a rotary piston carrier mounted on said shaft, compression pistons and explosion pistons arranged in pairs and slidably mounted in said carrier, the explosion pistons being formed with oblique working faces, piston rods, one connected to each pair of pistons, and a circular cam track having cams for engaging said piston rods to reciprocate the pistons.

15 9. In a rotary internal combustion engine, the combination with a casing having an arcuate explosion chamber, of a rotary piston carrier journaled in said casing, concentrically with said explosion chamber, and having transverse cylinders formed therein and arranged in pairs, explosion pistons and compression pistons arranged in pairs and sliding in said cylinders, means for projecting said explosion pistons into said explosion chamber, means for advancing said compression pistons to compress air in the cylinders in which the compression pistons are mounted, said explosion piston operating means acting to completely project the explosion pistons to the limits of their strokes in advance of the movements of the compression pistons to the limits of their compression strokes, and means for retracting the pistons, the parts being timed to bring the compression cylinders into communication with the explosion chamber after the explosion pistons reach the limits of their outward strokes.

20 10. In a rotary internal combustion engine, the combination with a casing having an arcuate explosion chamber, of a rotary piston carrier journaled in said casing, con-

centrically with said explosion chamber, and having transverse cylinders formed therein, and arranged in pairs, explosion pistons and compression pistons arranged in pairs and sliding in said cylinders, means for projecting said explosion pistons into said explosion chamber, means for moving said compression pistons to compress air in the cylinders in which the compression pistons are mounted, said explosion piston operating means acting to completely move the explosion pistons to the limits of their strokes in advance of the movements of the compression pistons to the limits of their compression strokes, and cam tracks for retracting the pistons, the parts being timed to bring the compression cylinders into communication with the explosion chamber after explosion pistons reach the limits of their outward strokes.

25 11. In a rotary internal combustion engine, the combination with a casing, having an arcuate explosion chamber, of a rotary piston carrier journaled in said casing concentrically with said explosion chamber, and having transverse cylinders formed therein, and arranged in pairs, one cylinder of each pair being a compression cylinder and having a port adapted to be brought into communication with said explosion chamber, explosion pistons and compression pistons in said cylinders, means for compressing air in said compression cylinders, and means for projecting the explosion pistons into the explosion chamber in advance of the final compression of the air in the compression cylinders.

30 12. In a rotary internal combustion engine, the combination with a casing having an arcuate explosion chamber, of a rotary piston carrier journaled in said casing, concentrically with said explosion chamber, and having transverse bores formed therein arranged in pairs, one bore of each pair forming a compression cylinder, and having a head provided with a port arranged to be brought into communication with the explosion chamber, explosion pistons and compression pistons in said cylinders, piston rods connected to said pistons, and cam shoes on said piston rods, a rotary cam shaft and a pair of cams on said cam shaft, one cam acting on the cam shoe of the explosion piston and the other cam acting on the cam shoe of the compression piston, the first mentioned cam being set in advance of the other, and acting on the cam shoe of the explosion piston to project it into the explosion chamber in advance of the final compression of the air in the compression cylinder.

FREDERICK J. KLINGLER.
